UNITED STATES PATENT OFFICE

169,529

TUMBLING TOY

Jack Baron, New York, N. Y.

Application July 28, 1951, Serial No. 16,064
In Canada June 14, 1951

Term of patent 7 years

(Cl. D34—15)

To all whom it may concern:

Be it known that I, Jack Baron, a British subject, resident of the city of New York, in the county of New York and State of New York, have invented a new, original, and ornamental Design for a Tumbling Toy, of which the following is a specification, reference being had to the accompanying drawing, forming a part thereof.

In the accompanying drawing:

Fig. 1 is a front view of a tumbling toy embodying my new design.

Fig. 2 is a side elevational view thereof.

I claim:

The ornamental design for a tumbling toy, as shown.

JACK BARON.
